UNITED STATES PATENT OFFICE.

HENRY ODEEN, OF PALO ALTO, CALIFORNIA.

PURIFICATION OF OILS.

No Drawing.

Application filed July 14, 1926. Serial No. 122,505.

This invention has to do with a process of refining oils and oil emulsions and more particularly the refining of fatty oils containing free fatty acids, and in its broader aspect includes the steps of adding to and mixing with such oils a finely divided solid material carrying a dry alkali and adding sufficient water to promote a rapid neutralization of free fatty acids and to agglomerate 10 the resultant soap stock.

One of the more important features of my invention resides in the employment in the process of a dry reagent hereinafter for brevity, referred to as "dry chemical" which 15 consists of a finely divided solid material carrying a dry substance, such as a dry alkali, capable of acting upon and neutralizing the free fatty acids of the oil. The finely divided carrier material may be inert 20 and non-absorbent and may be formed, for example, by thoroughly mixing the inert non-absorbent material (which may be) in powdered form with a concentrated solution of the alkali, such as caustic soda, drying 25 the said mixture, and grinding or pulverizing the resulting cake to a relatively fine powder. The surfaces thereof or substantial portions of the particles of powder will therefore be coated with and carry a closely adherent thin film of dry alkali. So formed 30 the dry chemical, when added to the oil, is in an ideal state or condition not only to serve as a scrubber to remove coloring, mucilaginous, colloidal and finely divided 35 suspended matters but also, when in the presence of water, to enable the reaction between the alkali and the acid components of the oil to proceed with avidity. However, I prefer, for reasons more fully pointed 40 out hereinafter, to employ a finely divided solid material which will absorb and be impregnated with the alkali in the step of forming the dry chemical, and I shall describe my invention in detail in connection 45 with such a finely divided solid absorbent material impregnated with a dry alkali. My process is also applicable to the refining of fatty oils in which a substantial proportion 50 of fatty acids have already been removed, in which case the alkali carried by the finely divided solid material serves to further purify the oil with respect to its coloring, colloidal, mucilaginous and finely divided suspended matters.

55 It may be stated at this point that if there

is present in the oil, which is rarely the case, a sufficient or an excess amount of water to satisfy the process then it is only necessary to add to such an oil the dry chemical in an amount sufficient to combine with and remove the moisture and other ordinary impurities from the oil; and by ordinary impurities is meant free fatty acids, coloring, colloidal, mucilaginous and finely divided suspended matters. In its broadest 60 aspect my invention, therefore, does not necessarily contemplate the addition of water where a sufficient amount thereof already exists in the oil to be refined. In all cases where water is to be added to the fatty oils, except where it is desirable to leave a colored oil as in the case of salad oils, I prefer to first add and thoroughly mix the dry chemical with the oil to be treated so as to obtain the beneficial results of a previous 65 scrubbing action upon the oil and thereby effect a more complete removal of the coloring, colloidal, mucilaginous and finely divided suspended matters.

The present invention relates to and involves what will herein be termed a "dry" process, since, while water is used in the operation, it is practically all absorbed by the reaction products and by the dry chemical added. In practice the process involves the 70 use of a limited amount of water so that it will be within the absorptive capacity of the reaction products, and the use of a dry chemical to produce the reactions and assist in absorbing the water. Soap is the 75 principal reaction product and this, together with the precipitated coloring, colloidal and finely divided suspended matters is left closely adherent to and entangled with the dry chemical in a substantially solid agglomerated state at the conclusion of the 80 treatment, whereas in the commercial processes heretofore generally used industrially, enough water is present so that these soaps and similar products existed as liquid solutions at this stage, hence these prior processes 85 can be termed "wet" processes. It is on account of their solid form and due to the absence of excess water that the said soap products and other impurities are more 90 insoluble in the oil, causing the same to more readily precipitate and be very easily removed in their entirety, from the purified oil in my improved process, and this I consider to be an important achievement. I 95

will now describe in detail what I consider to be the preferred embodiment of my invention.

The present invention specifically contemplates the use of a dry form of alkali or neutralizing agent (preferably caustic soda because of its comparatively low cost) existing in the form of a dry thin film or coating over the surface of, and preferably to some extent deposited within the pores or interior of some suitable dry finely divided solid material, preferably an inorganic absorbent material such as fuller's earth, or pulverized pumice stone. Pulverized charcoal also forms a suitable absorbent. Limited amounts of water are ordinarily added to the oil during the operation (e. g. before, during or after the addition of the pulverulent material, but not pre-mixed therewith) to aid and hasten the reaction between the alkali and the acid components in the oil, and also the said limited amounts of water control said reaction so that the action of the alkali is prevented from saponifying any appreciable amount of neutral oil but is confined to the neutralization of acidity and the removal of other impurities. If no water were added during the process and only the usual traces of moisture found in crude oils were present, the reaction would be extremely sluggish and would not proceed to completion for a long period of time, but the instant that water makes contact with alkali, the reaction proceeds with avidity and this takes place between the alkali and the acid components because of the latter's greater affinity for alkali than that existing between neutral oil and alkali. However fatty oils are readily saponifiable by caustic alkalies if any considerable amount of moisture is present; therefore in this method the amount of water introduced into the operation is so limited that a substantially dry oil is formed, and the soap formed is in a solid (and not dissolved) state. By thus controlling the reaction a more nearly quantitative separation of acid components can be effected than by using an excess of aqueous solution of alkali which is the common method employed in the practice of the art.

A slight excess of free water which ordinarily would be present or added during the operation would not be available for the saponification of any substantial amount of neutral oil because of the presence of the dry chemical and reaction products which have dehydrating properties. Even the films of soap which are formed in the reaction serve to assist in the dehydration of the oil after the essential reaction has taken place, for the reason that underneath the soap film, in the preferred form of my invention, exists a dry absorbent particle containing dry caustic alkali, and the dry alkali itself dehydrates in a powerful way; then there is also the

absorption of moisture taking place within the pores of the carrier material through capillary action. This process then, properly controlled, will produce an oil substantially free from moisture. It is understood that during the neutralizing operation agitation is employed so that there is uniform distribution of the neutralizing agent throughout the mass of the oil being treated.

Another noteworthy advantage of this method in all of its embodiments is that it will remove more coloring, mucilaginous, colloidal, and finely divided suspended matters than will the ordinary wet neutralizing methods. This may be partly due to the cauterizing action of the caustic alkali existing in such active state, and, in my preferred embodiment, partly due to the increased absorption power, for example, of the fuller's earth, which results in the above mentioned materials being rendered more insoluble and thrown out of their semi-soluble or colloidal state and thoroughly agglomerated much the same as the clarifying action which takes place in water purification when alum is added.

By the use of my method oil-washing and oil-drying equipment is not needed, and the bleaching equipment can be much simplified, thus lending to considerable economy in the apparatus used.

The present invention is broadly applicable to fatty oils in general, including those oils which are solid at normal temperature as well as those oils which are liquid at normal temperature, and is also applicable to mineral oil materials containing acids to be removed. The present application will be especially described in connection with normally solid oils (oils or fats that are solids at normal room temperature) of which I mention cocoanut oil, palm oil, palm kernel oil, tallow of various kinds, including tallow from animals and vegetable sources, etc. The process is also applicable to normally liquid oils such as cotton seed, rape, soy bean, cod liver, lard oils, as well as all kinds of fish oils, and claims specific to the treatment of normally liquid oils are included in my copending application Serial No. 122,504, filed concurrently herewith.

The present invention contemplates a distinctively dry process of refining oils, and while water is used and is important in the process, the absorptive capacity of the absorbent neutralizing agent and solid reaction products, is preferably always greatly in excess of the total amount of water present or added during the process.

As in my prior application 727,543, filed July 22, 1924, of which the present case is a continuation in part, fuller's earth will be discussed as a typical absorptive material in the dry chemical used. Other absorptive agents, such as kieselguhr, vegetable carbon

or charcoal, animal charcoal, clay of various grades, burnt clay, powdered coke and other inorganic absorptive materials can be used, or organic absorptive materials if desired, 5 such as dry soap or perhaps sawdust or wood meal, especially from non-resinous soft porous woods, can be used, as (although less advantageously) well as inert carriers which are not substantially absorbent e. g. sand. 10 Anhydrous salts or those partially hydrated and capable of taking up additional water of crystallization, such as sodium carbonate or sodium sulphate can likewise be employed as the carrier for the caustic alkali. Some 15 of these materials, notably sodium carbonate, might be considered as not inert since they might exercise more or less neutralizing action upon the free fatty acids.

As stated, water is employed in the process 20 in amount capable of promoting the reaction between the free fatty acids and the alkali, and ordinarily relatively pure water (e. g. ordinary tap water) is preferred. However, the use of water containing dissolved 25 salts or other dissolved substances is not precluded. Thus it might be advisable to employ, instead of pure water, solutions of common salt, aluminum sulphate or borax, or other substances which may to some extent 30 precipitate or destroy coloring matter in the oil or which may to a considerable extent assist in dragging down and precipitating colloidal or suspended matters, or albuminous matters or other gummy or mucilaginous substances present in the oil. 35

The amount of water to be used in the process will vary, depending largely upon the quantity of free fatty acids present in the oil. With oils of ordinary free fatty 40 acid content (say 3 to 7% free fatty acid content) an amount of water equal to 0.5% up to 2% or 4% or so, will generally be satisfactory, although somewhat larger amounts than this may be used if desired. In some 45 cases commercial crude fatty oils (say cocoanut oil) frequently contain more or less water, say up to 0.7% or even considerably more than this. With oils naturally containing such quantities of water, and especially if the free acid content is low, it 50 may not be necessary to add further amounts of water during the process. Generally stated, I find it advisable to add more water if the oil is high in free fatty acid content 55 than would be needed if the oil is low in free fatty acids. Thus with a 5% F. F. A. cocoanut oil, I may use about 2% of water, and with a 10% F. F. A. cocoanut oil, it may be necessary to use as much as 3.5 to 4% of 60 water. The percentages are based on the amount of oil.

The amount of water above stated can be varied between more or less wide limits.

The water can be all added before the introduction of the dry chemical, or can be added

after the addition of the dry chemical, or can be added during the addition of the dry chemical, but separately therefrom. I do not mix the water with the dry chemical and add the said mixture to the oil to be 70 treated, since this would be wasteful and I would not get the complete results of the process. In treating cocoanut oil, and many kinds of similar oils, I preferably add all the water (aside from that naturally present 75 in the crude oil) after the addition of the dry chemical (i. e. the solid absorbent material impregnated with dry alkali) and preferably after well agitating the mixture of the warm liquid oil and dry chemical for 80 a while (say for 10 to 30 minutes, more or less). This is because with such oils as are herein particularly referred to, the agitation with the dry chemical considerably reduces the color and removes colloidal mucilaginous and fine suspended matters, which 85 is of importance in the treatment of such oils. The modification of adding the water before the addition of the dry chemical, as herein disclosed, is claimed specifically in a 90 copending case Serial No. 122,504.

Preferably the amount of the dry chemical used (say fuller's earth impregnated with dry caustic soda) should (in conjunction with the soap formed) have an absorption 95 capacity for water considerably more than the total amount of water present (i. e. that originally present in the oil, plus that added plus that formed in the reaction of the free fatty acid on caustic alkali). 100

The amount of the dry chemical to be added will depend on numerous factors, including the amount of free fatty acids in the oil to be treated, the amount of decolorization to be effected and the amount of mucilaginous 105 and gummy materials in the oil. For ordinary purposes 2 to 5% (based on the amount of the oil) will be found to be a convenient amount of the dry chemical to use, but in some cases, particularly where it is desired to produce a considerable amount of decolorization of the oil, I may use 10% or even more. 110

The amount of active neutralizing reagent, say caustic soda, should preferably 115 be in excess of the amount which theoretically would be necessary for combining with and neutralizing the total free fatty acids in the oil under treatment if it is desired to completely remove such acids. An excess of 120 from 50 to 150% over the theoretically required amount of caustic soda is recommended in some cases. The reason for this is that the absorbent material, which is the preferred form of carrier, will contain some alkali undecomposed or not reacted upon, at the end of the treatment. 125

The dry chemical which I prefer to use may, for instance, be formed by impregnating a dry inert absorbent material, such as 130

fuller's earth or any of those above referred to, with a solution, preferably a highly concentrated solution of caustic soda, then I dry the so impregnated material, for example in an oven or pan at a temperature of 200 to 300 or to 400° F., or, if desired, much higher temperatures can be used. With 100 parts of ordinary fuller's earth, I may (for example) use 130 parts of a saturated (say 10 55%) solution of caustic soda. The material is thereafter dried and the resulting cake is ground up or pulverized to a relatively fine powder. In other cases, with 100 parts of fuller's earth satisfactory materials 15 have been prepared when using from 80 to 150 parts of saturated caustic soda solution or weaker solutions containing 10-45% NaOH, more or less. Such a dry chemical may be very advantageously employed in refining oils in which a substantial amount of 20 the free fatty acids have already been removed.

I have referred above to drying the impregnated fuller's earth, but it is to be understood that this drying does not have to be complete to the extent of removing every trace of water. The material is dried sufficiently so that it will readily absorb and take up water present in or added to the oil. The 25 term "dry" will be so understood herein as applied to the impregnated carrier.

Complete impregnation in the manner above described followed by drying, gives a satisfactory chemical to use. However in 30 some cases, caustic soda and fuller's earth can be well ground and triturated together, say in a mortar or edge-runner mill. If the mill is open to the atmosphere the caustic may take up more or less moisture from the 35 atmosphere during this step, or some water can be added to the mass or to the materials, before or during the grinding and mixing operation. Thus this will give an intimate 40 association and substantially an impregnation. This product can be then dried and 45 powdered, as above described.

In practising the method of oil refining and purification in its preferred form, I generally warm up the oil to a temperature at 50 which it is freely liquid and at which it has a sufficiently low viscosity to be readily treated. This temperature will depend upon the particular oil, and with cocoanut oil a temperature of 110 to 130° F. is very satisfactory. Irrespective of the particular oil 55 treated (if a fatty oil), I preferably do not heat to over 140° F. at, and above which the heat is likely to "set" the color and otherwise injure fatty oils. Some water can then 60 be added, or if desired a portion of this water can be added at this stage and the balance of it added later. Preferably however, I do not add the water until after the dry 65 chemical has been added to and well agitated with the oil.

The alkali impregnated solid material (or "dry chemical") is first added to the oil, for example by being sifted or sprinkled upon the top of the agitated body of oil in a refining tank provided with a suitable agitator. The oil is preferably agitated during and for some time after (say 10 to 60 minutes) this chemical has been added. Then the water to be used can be added at this stage. The water is preferably added as a 70 fine spray directed downwardly upon the top of the agitated mass of oil carrying the fine dry chemical in suspension. The "break" will occur after only a few minutes further agitation. I may add the water from a 75 spray nozzle, said nozzle being adjusted to give a fine spray. I preferably watch the oil carefully and when large streaks of clear oil and large clots of a sponge-like appearance show in the oil, I then shut off the 80 water inlet, and allow the agitation to continue for a few minutes longer (say 1 to 5 minutes, or more). During this continued agitation, the water in the oil (i. e. the last 85 of the water added) is absorbed by the solid material, that is, the reaction products and the dry chemical.

Instead of using plain water, in the preceding paragraph, I may use a 5 or 10% solution of common salt, alum or the like. 90 As is well known, common salt acts to render soap less soluble.

The oil and materials contained therein are then preferably allowed to settle and sedimentation will occur quite rapidly even 100 in a large bulk of oil it will be found that the solid matter will practically all settle out of the oil, within half an hour or an hour, and the clear oil in the upper part of the receptacle can then be passed through 105 the filter press (or other separating device) and sent to storage as refined oil. This settling is more or less optional and the entire mass in the refining tank, say a few minutes after the water is shut off, could be 110 pumped into a filter press or other separating device. The settling and separate removal of the clear oil is an advantage as the larger part of the soap stock does not have to go to the filter press at all. 115

Due to the powerful drying or dehydrating properties of the dry chemical and the water-absorbing properties of the soap formed, the filtered refined oil will be found to be very bright and clear, and analysis 120 will show practical absence of water therein, or say usually well below 0.25% and in most cases below 0.1% of water.

The sludge in the bottom of the refining tank can be drawn off and this will carry 125 more or less entrained oil and this latter can be practically all separated from the solid material in a centrifugal basket separator or other suitable device. This oil can then be passed over to the filter press 130

above referred to, thence to the storage tanks. The remaining solid material can be worked up in any desired manner, for example by agitating with hot water and 5 dissolving the soap stock which may be disposed of in any preferred manner. The fuller's earth, when that material is employed as a carrier for the alkali, does not, of course, dissolve in water during the separation of the soap therefrom, and this 10 fuller's earth can again be impregnated with caustic alkali and re-used in the process. Thus the fuller's earth or similar carriers can be reused many times if desired.

15 When other solid absorbent chemically inert insoluble carriers such as clays, charcoal, etc., are employed, the above mode of regenerating same for reuse, will be satisfactory. When anhydrous soda or soap 20 powder is used as a carrier, the solid material from which the oil has been removed can be sold as soap stock or worked up into soap products, e. g. by adding resin or more fatty acids if a more nearly neutral soap is 25 desired, and if desired adding some water. When powdered abrasive such as kieselguhr or pumice is used as the carrier, the solid product separated from the oil can be usefully incorporated into scrubbing powders, 30 etc.

In the process of refining, as herein described, it is generally an object to remove the free fatty acids as completely as possible. However, in some instances, it would 35 be sufficient to use far less than enough of the dry chemical and of water to accomplish this. Thus a highly colored and highly odoriferous oil might be treated with only enough of the dry chemical and water, to 40 somewhat brighten its color and remove some of its odorous substances while removing only half or less of its free fatty acid content to cheaply improve a soap-making oil.

45 In a modified form of the process, I may add somewhat more water, even continuing the addition of water after the "break" say while agitating. I can then settle and decant or filter, if desired, although these 50 operations at this stage are unnecessary. I can then suitably remove the excess of water, as by adding more of the alkaline absorbent reagent, or other water-absorbing substance, followed by a short agitation and 55 filtration. This modification may sometimes produce more bleaching or more complete removal of colloidal or suspended matters, but is not generally recommended.

In another modification of the process, I 60 can add alternately several small amounts of water and of the dry chemical, while agitating, until the desired amount of purification has been effected, and the oil may or may not be filtered, say after each addi-

tion of chemical has had a chance to act. 65 In this way, a minimum amount of chemical would effect a maximum amount of purification. Such a modification however might cost more in the way of added handling, filtering, etc. The total amounts of 70 water and dry chemical used in this modification may be the same as in the above examples, or less, and the two materials are added alternately in small amounts at a time. The operation is otherwise the same 75 as above.

I have referred above to the use of caustic soda as the preferred neutralizing agent. Other alkalies such as the carbonates, oxides and hydroxides of the alkali metals and 80 the alkaline earth metals, or ammonia gas, or salts of weak acids which give a basic reaction, such as borates, silicates, or other agents capable of neutralizing free fatty acids, can be used.

I have also referred to the use of strong solutions of alkali for impregnating the absorbent carrier materials. In some cases, however, relatively weak solutions or impregnation with only a small amount of 90 alkaline solutions may be advisable. Thus I may prepare "dry chemical" containing only 2 to 10%, more or less, of NaOH, which would be very suitable when it is more especially desired to accomplish decolorization, precipitation of colloidal matters, etc., with only a small amount of neutralization of free fatty acids, as when treating oils in which the fatty acid content is quite low. A special example of this is the treatment of 100 cocoa fat from which it is desired to remove a large amount of coloring matters, colloidal and suspended matters, etc., although the free fatty acid is usually very low. For ordinary purposes, however, as 105 where the removal of a normal fatty acid content is desired, the amount of NaOH in the dry chemical may be higher, say from 10% up to 45%, more or less.

In one of the above examples, I have discussed the drying of the impregnated absorbent, e. g. fuller's earth. When soap powder is used as the absorbent, I may make a mixture of soap, alkali and water in any desired proportions and dry this mixture 110 say in a vacuum drier, to eliminate the use of high temperatures. This drying should be carried sufficiently far to give a readily pulverizable product and may contain a small proportion of water. This 115 dried material is then reduced to the desired state of fineness.

The advantages of my invention are: (a) The yield of neutral oil from the refining steps is very greatly increased because the 120 dry process practically precludes the formation of emulsions. In the ordinary methods of refining this neutral oil loss is

one of the greatest, and oftentimes the greatest item of refining cost, but by my method this item of refining cost is materially reduced. (b) The absorption losses in the bleaching and filtering step of the wet process methods are reduced to a fraction thereof because in my method the clear oil from the refining tank may be run directly to the filter presses without the addition of decolorizing clays or carbons, thus eliminating absorption losses in these materials and thereby also increasing manyfold the number of batches that may be run through the filter press before its capacity has been reached. (c) Lower cost, (as compared with other purification processes) because of less labor and equipment required to carry on the process, and because of a greater yield of neutral oil. (d) A further substantial reduction in cost and simplification of the whole process is effected by the decolorizing action taking place in the same stage with the neutralization of the free fatty acids. (e) A great saving in time is effected, since washing and settling processes are eliminated. (f) It becomes unnecessary to subject the oil to high drying temperatures, thereby insuring a better quality of oil, particularly when the same is to be used for edible purposes. (g) It practically precludes the formation of free fatty acids in the oil under treatment since the oil during processing does not encounter the usual washing and high heating steps. (h) The neutral oil is practically completely freed of soap in one operation. (i) The working up of the soap stock is simplified because of the practical absence of emulsions, which are always a source of large refining loss, and cost of handling. (j) The process presents especial value in the treatment of certain oils, such as castor oil, which, when subjected to the wet neutralization methods, produce very troublesome emulsions or solutions, or both, in the refining kettle. My process completely eliminates the formation of such emulsions and solutions.

I have described in detail several embodiments of my invention but it is to be expressly understood that I do not limit myself thereto or to the details related in connection with the specific embodiments described. I have also indulged in some theoretical discussions of what actually takes place in the practical use of my invention to more clearly elucidate the principles thereof. I may be mistaken about some of these theoretical considerations but I do know that when the steps of the process are carried out in the manner clearly indicated, no difficulties will be encountered in practicing my method and that substantial results, some of which have been referred to, will be achieved.

Further examples, for the purpose of further illustration:—

A mineral oil material containing acids, for example the product obtained by treating lubricating mineral oil with sulfuric acid, settling and withdrawing sludge, (consisting largely of hydrocarbons, and containing some sulfonic acid compounds of hydrocarbons, some sulfonated oils, some free sulfuric acid and some water) is treated with 1 to 5% (more or less) of the dry chemical above referred to, well agitated, and filtered or centrifuged.

I have above referred to dry soap as the carrier in the dry chemical. Thus I may start with the normally solid soap product produced in the present process, which may contain about 50% of water and about 50% of actual soap. Put an amount of this into a steam jacketed kettle, heat to liquefaction, add about an equal amount of flake or powdered caustic soda, stir until a homogeneous mass is formed, cool to solidification, comminute or powder to as fine a state of division as possible. This may or may not be further dried, and constitutes a suitable example of a dry soap-and-caustic-soda reagent. Add 1 to 10% of this to the oil at say 80° to 100° F., agitate for a short time, add about 1 to 10% of water, continue agitation, settle and complete the process as above.

The soap stock in this case would consist of impure soap containing about 40-60% (more or less) of water, and some free caustic soda and some free oil, suspended matters, etc., and may be sold to the soap industry as such.

As above stated, anhydrous salts can be used as the vehicle. Anhydrous soda, (e. g. soda ash) may be mentioned. I may mix 100 lbs. of dry soda ash with 150 lbs. of hot caustic soda solution of 66% strength. Dry this, while grinding, in a vacuum drier. This product can be used and the residue disposed of as in the previous example.

In the above I have referred to using various clays instead of fuller's earth.

For example I mix 30 parts of powdered clay with 20 parts of water to make a fairly plastic mass. To this I add a hot solution of caustic soda containing 12 parts of NaOH and 6 parts of water. I then mix the entire mass well and dry and grind to about the fineness of Portland cement. I add to cotton seed oil 1.5% of this powder (based on the weight of the oil) stir well for 15 minutes, add 1.5% of water, again stir well for 15 minutes, then add another 1% of the dry powder, again stir to thoroughly mix, then add about 1.5% of water, again stir for 15 to 30 minutes and filter or separate by other suitable means. This oil so treated is practically neutral and of greatly improved

color and flavor and is clear and dry, and practically entirely free of soap and other impurities.

What I claim and desire to secure by Letters Patent is:

1. In a process of refining a fatty oil whose fatty acids have not previously been removed, and of which the water content is below 4%, the steps which comprise adding to such oil a finely divided solid absorbent material impregnated with a dry alkali and separately adding a sufficient amount of water to promote a rapid neutralization of fatty acids and to agglomerate the soap stock without causing appreciable emulsification, the water being absorbed by the solid material and solid reaction products yielding an oil which is substantially anhydrous.
  2. In a process of treating fatty oil the steps of adding to such an oil, a finely divided solid absorbent material impregnated with a dry alkali and having present at some stage of the treatment a sufficient amount of water to promote rapid reaction between the said alkali and acid components of the oil, such amount of water being sufficient to agglomerate the resulting products of such reaction without causing appreciable emulsification, the water being absorbed by the solid material and solid reaction products yielding an oil which is substantially anhydrous.
  3. In a process of refining a fatty oil the steps of adding to such oil, while warm, a finely divided solid material carrying intimately mixed therewith a dry alkali there being sufficient water present at some stage of the process to promote rapid reaction between the alkali and acid components and to agglomerate the resultant reaction products and thereafter separating the insoluble materials from the oil without causing appreciable emulsification, the water being absorbed by the solid material and solid reaction products yielding an oil which is substantially anhydrous.
  4. In a process of refining fatty oils for neutralization of the fatty acids and decolorization of the oil, the steps of adding thereto a finely divided solid absorbent material impregnated with a dry alkali and agitating the mixture and separately adding at some stage of such treatment, water in an amount sufficient to promote a rapid reaction between the alkali and fatty acids and to agglomerate the resulting reaction products without causing appreciable emulsification, the water being absorbed by the solid material and solid reaction products yielding an oil which is substantially anhydrous.
  5. The process of refining fatty oil whose acids have not previously been removed and which oil contains coloring matter colloidal and finely divided suspended matter, which
- process comprises adding to and agitating with such oil, a finely divided solid material, the particles of which carry a dry alkali intimately bonded thereto, and separately adding water at some stage of the process, to cause by such steps a precipitation of coloring matter, colloidal and finely divided suspended matter and a neutralization of the fatty acids, the amount of such water being sufficient to promote a rapid neutralization of the fatty acids and agglomeration of the resultant insoluble products without causing appreciable emulsification, the water being absorbed by the solid material and solid reaction products yielding an oil which is substantially anhydrous and thereafter removing the insoluble material from the oil.
6. In a process of refining fatty oils containing free fatty acids and some water, the steps of adding to and mixing with such an oil a dry finely divided solid material carrying a dry alkali in an amount sufficient to remove the water and other impurities from the oil, and thereafter adding sufficient additional water to promote rapid neutralization of the oil and to agglomerate the resultant soap stock.
  7. A process of refining fatty oils containing free fatty acids, which consists only in the sequential steps of adding to and mixing with such an oil a dry finely divided solid material carrying intimately incorporated therewith a dry alkali, adding sufficient water to promote rapid neutralization of the oil and to agglomerate the resultant soap stock, and thereafter separating the insoluble materials from the oil.
  8. A process of refining fatty oils containing free fatty acids, which includes the steps of adding to and mixing with such an oil a finely divided solid soap carrying a dry alkali, and at some stage of the process adding sufficient water to promote rapid neutralization of the oil and to agglomerate the soap that was added and the soap that is formed in the reaction.
  9. In a process of refining a fatty oil containing free fatty acids, the improvement which includes mixing such oil with a finely divided dry solid material inert to alkali, carrying a dry solid alkali in an amount sufficient to neutralize such free fatty acids, and adding to such mixture only a sufficient amount of water to promote rapid neutralization and to agglomerate the resultant soap stock without leaving substantial amounts of the soap stock in solution.
  10. In a process of refining a fatty oil containing free fatty acids, the improvement which includes mixing such oil with a finely divided dry solid material carrying a dry solid alkali in an amount sufficient to remove coloring, mucilaginous, and finely suspended matters and to neutralize such free

fatty acids, and adding to and agitating with such mixture only a sufficient amount of water to promote rapid neutralization and to agglomerate the resultant soap stock.

5. 11. In a process of refining a fatty oil containing free fatty acids, the improvement which includes mixing with such oil a finely divided solid absorbent material impregnated with a dry alkali, said alkali being in amount in excess of that theoretically required to neutralize such free fatty acids, and adding to such mixture a sufficient amount of water to promote rapid neutralization and to agglomerate the resultant 10 soap stock, but not sufficient to dissolve any substantial portion of said soap stock.

12. In a process of refining a fatty oil containing free fatty acids, the improvement which includes mixing with such oil a dry finely divided solid material intimately mixed with a dry alkali, said alkali being in amount in excess of that theoretically required to neutralize such free fatty acids, and adding to such mixture a sufficient 20 amount of water to promote rapid neutralization and to agglomerate the resultant soap stock, but not sufficient to dissolve any substantial amount of said soap stock such operation being conducted at a temperature 25 at which the oil is freely liquid, but below 30 140° F.

13. In a process of refining a fatty oil containing free fatty acids, the improvement which includes mixing such oil with a finely 35 divided solid material carrying a dry alkali, and adding to and agitating with such mixture only a sufficient amount of water to promote rapid neutralization and to agglomerate the resultant soap stock.

40. 14. In a process of refining a fatty oil from which the free fatty acids have not been removed, the improvement which includes warming the oil sufficiently to render the same thoroughly liquid, mixing such 45 warm oil with a dry form of alkali carried by the surfaces and in the pores of a solid, finely divided, material of a porous absorbent nature, the alkali being present in an amount sufficient to remove coloring, mucilaginous, and finely suspended matter and 50 to neutralize such free fatty acids, and adding to and agitating with such mixture a sufficient amount of water to promote rapid neutralization and to agglomerate the resultant 55 soap stock.

15. A process of refining a fatty oil containing free fatty acids, which comprises adding to and mixing with such oil, while warm enough to be freely liquid, a finely 60 divided solid material carrying a dry substance in intimate contact therewith which substance is capable of acting upon and neutralizing such free fatty acids, moistening with water and agitating the mixture of 65 such oil and solid material sufficiently to

promote rapid neutralization and to agglomerate the resultant solid impurities, and thereafter separating the solid impurities from the purified oil.

16. In a process of refining a fatty oil 70 containing free fatty acids, the steps which include forming a warm mixture of such oil and a dry finely divided solid absorbing material carrying in intimate contact therewith, a dry fixed alkali, and moistening such 75 mixture with water whereby soap is formed from the fatty acid and alkali.

17. In a process of refining a fatty oil containing free fatty acids, the steps which include mixing with such oil a dry finely 80 divided solid material the particles of which carry intimately bonded thereto, a dry fixed alkali in an amount sufficient to combine with such free fatty acids, and moistening said mixture with water, whereby soap is 85 formed from the fatty acid and alkali.

18. In a process of refining a fatty oil containing free fatty acids, the steps which include mixing with such oil a dry finely 90 divided solid material, the particles of which carry intimately bonded thereto a dry fixed alkali in an amount sufficient to combine with such free fatty acids, and adding a small percentage of water to said mixture, the total amount of water present, including 95 that added, being insufficient to leave a substantial amount of the soap in a dissolved state.

19. In a process of refining a fatty oil containing free fatty acids, the steps which 100 comprise adding to such oil a dry finely divided solid material intimately mixed with a dry fixed alkali and thereafter adding an aqueous material chemically inert to caustic alkali capable of hastening the 105 reaction between the free fatty acids and the alkali, the amount of water in such aqueous material being insufficient to leave any substantial amount of soap in solution.

20. A process of refining normally solid 110 fat containing free fatty acids, which comprises the steps of melting the fat and adding thereto, while in a freely molten state, a dry finely powdered reagent carrying a dry caustic alkali intimately bonded to a 115 solid bulking agent by drying a solution of caustic alkali on said bulking agent and well agitating the mixture of such oil and alkalinized reagent.

21. A process of refining normally solid 120 fat containing free fatty acids which comprises the steps of adding thereto, while in a freely molten state, a dry finely divided solid material carrying a solid dry alkali intimately bonded thereto, and separately 125 adding a small amount of water sufficient to produce a rapid "break" but insufficient to leave the major part of the soap stock in solution.

22. A process of purifying and deacidify- 130

ing a normally solid fatty oil which comprises adding thereto while said oil is molten, a dry solid carrier intimately admixed with a caustic alkali, and separately from such 5 step, adding enough aqueous liquid compatible with caustic alkali to cause the alkali to react with free acids in the oil, the amount of such aqueous liquid so added being insufficient to leave the major part of the soap 10 produced, in solution.

23. A process of purifying and deacidifying cocoanut oil containing not over 10% of free fatty acids, while said oil is in a molten state, which comprises adding a substantially dry solid carrier intimately associated with caustic alkali, the amount of such alkali being more than chemically equivalent to the free fatty acids in the oil treated, and separately therefrom adding such 20 an amount of water as will hasten the reaction between such alkali and the free fatty acids in the oil and also will be taken up by the said absorbent carrier, excess of alkali used and soap formed, to leave the soap 25 formed in the solid state.

24. A process of purifying and deacidifying normally solid fat, which comprises treating molten normally solid fat containing free fatty acids with about 2 to 10% 30 of a dry reagent, such dry reagent comprising a solid material carrying intimately incorporated therein, a caustic alkali, and separately with enough water to produce a

rapid break, the amount of such dry reagent being always sufficient, in conjunction with 35 the soap produced, to absorb the entire amount of water present in the fat and added, and the caustic alkali in said dry reagent added being in excess over the amount theoretically necessary to neutralize 40 all the free fatty acids present in said fat, such water and dry reagent being added separately but in any desired order, and the fat being at not above 140° F., during such treatment, and agitating the mixture.

25. A process of purifying and deacidifying a fatty oil which comprises treating a fatty oil containing free fatty acids with about 2 to 10% of a dry reagent, such dry reagent comprising a solid absorbent material carrying intimately incorporated therein, a caustic alkali, and with enough water to produce a rapid break, the amount of such dry reagent being always sufficient, in conjunction with the soap formed, to absorb 50 the entire amount of water present in the oil and added, and the caustic alkali in said dry reagent added being in excess over the amount theoretically necessary to neutralize 55 all of the free fatty acids present in said oil, such dry reagent and water being added separately and in the order here stated, and agitating the mixture.

In testimony whereof, I have hereunto set my hand this 13th day of July, 1926.

HENRY ODEEN.
